UNITED STATES PATENT OFFICE.

MATTHEW W. LYNCH, OF MADISON, WISCONSIN.

LOCK-BUCKLE FRAME.

SPECIFICATION forming part of Letters Patent No. 695,405, dated March 11, 1902.

Application filed May 9, 1900. Serial No. 16,083. (No model.)

To all whom it may concern:

Be it known that I, MATTHEW W. LYNCH, a citizen of the United States, residing at Madison, in the county of Dane and State of 5 Wisconsin, have invented a new and useful Lock-Buckle Frame, of which the following is a specification.

My invention relates to improvements in lock-buckle frames which are so constructed 10 that the buckle-tongue is pivoted above the strap to be secured and in which the said tongue when in a locked position passes downward through the strap and into a recess in the body or casting, the present invention being designed as an improvement upon the 15 construction shown in my Patent No. 573,093, dated December 15, 1896, having for its objects, among others, to reduce the weight, lessen the cost of manufacture, and to provide 20 a better and neater-looking buckle when attached to a strap.

The novelty resides in the peculiarities of construction and the combination, arrangement, and adaptation of parts, all as more 25 fully hereinafter described, shown in the drawings, and then particularly pointed out in the appended claim.

The invention is clearly illustrated in the accompanying drawings, which, with the letters of reference marked thereon, form a part 30 of this specification, and in which—

Figure 1 is a side elevation with the strap in section and a portion of the buckle-frame broken away and parts in section with the 35 tongue in its locked position. Fig. 2 is a plan with the tongue in the recess, the strap not being shown. Fig. 3 is a rear view of the frame with the lugs in section and the tongue thrown up out of the recess. Fig. 4 is a front view 40 of the staple before being riveted to the frame, the tongue being removed.

Similar letters refer to similar parts throughout the several views.

The frame *a* is a casting of metal the sides 45 of which are parallel through the central portion and rounded on the two front corners and has rounded lugs *f* projecting from each side on the rear corners. (See Fig. 2.) In thickness the frame is about equal from the 50 rear (marked *x*) to about two-thirds the distance forward. Then it is reduced from the

top to allow the strap to be attached in the same manner as described in the patent granted to me December 15, 1896, No. 573,093. The mortise *g*, Fig. 1, is cored through the 55 frame from side to side and is drifted smooth to receive a lock-bolt *i*, which is fastened in both locked and unlocked positions and made and operated the same as described in said Patent No. 573,093.

The staple *b*, Fig. 4, is reduced in diameter 60 at the center, forming a bearing for the tongue *c*, and is also reduced at the two downwardly-projecting ends, forming tenons which are inserted into holes drilled through the lugs *f* 65 on the frame *a* and headed to the same, as shown clearly in Figs. 1 and 3. The tongue *c* is a piece of rod of the proper size and length bent around the staple at one end and fitted to the bearing, as shown in Figs. 1, 2, 70 and 3.

It will be seen by reference to the drawings that the construction shown is much easier and cheaper to manufacture than the frame described in my former patent, and for 75 equal strength is of one-third less weight. It is also clear that the staple at its two upper corners or curves has greater strength than the arrangement for supporting the tongue, as shown in said former patent.

When the tongue is in the position seen in Fig. 2, with its lower end extending into the recess *h* in the top of the casting, which recess intersects the mortise *g*, and the flat bolt *i* moved into the locked position, the latter 85 prevents the tongue from being moved on its pivot, so as to be swung out of the recess; but when the bolt is moved endwise in the mortise *g*, so that the notch in the bolt (seen in Fig. 2) comes coincident with the said recess and the end of the tongue, the latter 90 may be swung up into the position seen in Fig. 3.

Having thus described my invention, what I claim as new, and wish to secure by Letters 95 Patent, is—

In a lock-buckle frame, the combination with the body *a* having lugs *f* and transverse mortise *g* for the bolt, and a recess in its face communicating with the said mortise, of a 100 staple having tenons passed through said lugs and secured to the under face of the said body

in recesses therein, a tongue pivoted on the cross portion of said staple, and a flat bolt mounted to move endwise in said mortise and to intersect said recess when in its locked position and prevent removal of the said tongue, substantially as shown and described.

5 In testimony whereof I have signed my

name to this specification in the presence of two subscribing witnesses.

MATTHEW W. LYNCH.
